UNITED STATES PATENT OFFICE.

FOLKE ENGLE BRANDT, OF HIGH WYCOMBE, ENGLAND.

WINDOW.

Application filed September 28, 1921. Serial No. 503,965.

To all whom it may concern:

Be it known that I, FOLKE E. BRANDT, a subject of the King of Sweden, residing at Wynton Works, High Wycombe, Bucks, 5 England, have invented a new and useful Window, of which the following is a specification.

It is the object of this invention to provide simple but novel means whereby a window 10 dow sash may be raised and lowered, opened and closed by a swinging movement, and be held securely in any position which it may assume.

It is within the province of the disclosure 15 to improve generally and to enhance the utility of devices of that type to which the invention appertains.

In the drawings:—Figure 1 shows in elevation, a device constructed in accordance 20 with the invention; Figure 2 is a longitudinal section showing one sash in open position; Figure 3 is a fragmental front elevation wherein parts are broken away; Figure 4 is a section taken on the line 4—4 of Figure 1; Figure 5 is an elevation showing one edge of the slide; Figure 6 is a section on the line 6—6 of Figure 3.

The numeral 1 marks a window frame carrying stop and parting strips 2 defining 25 guide ways 3 wherein slides 4, in the form of bars, are mounted for reciprocation. Sashes 5 are disposed between the slides 4. Washer strips 6 of any desired form are mounted on the inner edges of the stiles of 30 the sashes 5. Pivot elements 7 are mounted in the stiles of the sashes 5 and in the slides 4, intermediate the ends of the stiles and the slides. Wing nuts 8 are threaded on the outer ends of the pivot elements 7 and are 35 adapted to bear against the washer strips 6. Superposed nuts 9 are threaded on the outer ends of the pivot elements 7 and are received for rotation in recesses 10 fashioned in the slides 4. The outermost nut 9 has a kerf 11, 40 and the inner nut 9 may be similarly equipped, to the end that the nuts may be manipulated by a spanner or like tool.

The stile of each sash 5 has one or more bores 12 adapted to be alined with bores 14 45 in the slides 4. A washer plate 15 is mounted on the stile of each sash 5 at the end of the bore 12. A keeper plate 16 is attached by securing elements 17 to each slide 4 and has an internally threaded projection 20 received in the bore 14 of the slide 4. Screws 55 18 are journaled in the washer plate 15 and

are provided with turning heads 19, the screws passing through the bores 12 and 14, and being threaded into the projections 20 of the keeper plates 16. 60

The screws 18 serve to hold the sash 5 securely in a closed position, in alinement with the slides 4, and under such conditions, the slides and the sash may be reciprocated vertically, after the manner of a common window sash. The screws 18 may be removed, whereupon the sash 5 may be swung on the pivot elements 7, and be held in adjusted positions by tightening the wing nuts 8. The sash, having been tilted, may be raised and 65 lowered, along with the slides 4. It is possible to reverse the sash 5 about a horizontal axis, if desired. Especial attention is directed to the fact that the nuts 9 are countersunk into the slides 4, the keeper plates 16 being countersunk likewise, and the construction of the slides being such that they may be mounted in any ordinary window frame, without requiring any changes whatsoever therein. 70 75 80

I claim:—

A device of the class described comprising a frame, slides mounted for reciprocation in the frame, a sash mounted pivotally intermediate its ends on the slides, the sash including a stile, one slide and the stile being provided with cooperating transverse bores, the bores being formed directly in said slide and said stile, each bore being of a common diameter from end to end, both bores being 85 of the same diameter, and the bore of the stile extending entirely through the stile, a plate countersunk into the outer surface of said slide and interposed between said slide and the frame, the plate having an integral internally threaded cylindrical projection 90 extended toward said stile into the bore of the slide and fitting closely therein, a washer plate secured to the outer edge of the stile and having an opening of less diameter than the bore of the stile, the washer plate constituting a closure for the bore of the stile, and a screw of less diameter than the bores, the screw being journaled in the opening of the washer plate and having a head adapted 95 to engage the washer plate, the screw being threaded into the projection, and the washer plate serving to centralize the screw with respect to the bore of the stile. 100

In testimony that I claim the foregoing 110 as my own, witness my hand.

FOLKE ENGLE BRANDT.
